UNITED STATES PATENT OFFICE.

ANDREW M. BELFIELD, OF CHICAGO, ILLINOIS, ASSIGNOR TO THE CABLE COMPANY,
OF CHICAGO, ILLINOIS, A CORPORATION OF ILLINOIS.

MECHANICAL MUSICAL INSTRUMENT.

1,150,653.

Specification of Letters Patent. Patented Aug. 17, 1915.

Application filed April 22, 1905, Serial No. 256,833. Renewed March 19, 1915. Serial No. 15,575.

To all whom it may concern:

Be it known that I, ANDREW M. BELFIELD, a citizen of the United States, residing at Chicago, in the county of Cook and State of Illinois, have invented a certain new and useful Improvement in Mechanical Musical Instruments, of which the following is a full, clear, concise, and exact description, reference being had to the accompanying drawings, forming a part of this specification.

My invention relates to self-playing musical instruments such as piano players either of the cabinet or interior varieties.

15 The principal object of the invention is to permit a sudden accent of any note or series of notes in the playing of a composition, and especially to permit this to be done whether the playing at the time be soft, loud or

20 medium.

Another object of the invention is to permit one particular part of the composition, as for example the treble or the bass, to be accented without reference to the character 25 of the playing at the time, independent of the other part.

A further object of the invention is to accomplish the foregoing and other desirable ends in a simple and expeditious manner.

In the accompanying drawings, Figure 1 is a view partly in plan and partly in horizontal section, of a cabinet piano player embodying my present invention; Fig. 2 is 35 an end view of a portion of the same; Figs. 3 and 4 are views of details of construction; Fig. 5 is a view similar to Fig. 1 of the invention applied so as to accent either the bass or treble independently of one another, 40 Fig. 5 being taken on line 5—5 in Fig. 6, but showing also the tracker board and associated parts; Fig. 5^a is a detail view on a cross section taken through the valve boxes and looking from the rear of Fig. 5; Fig. 6 45 is a vertical section of the same taken on line 6—6 in Figs. 5 and 7; Fig. 7 is a rear view of a part of the device; Fig. 8 is a view of details of construction.

Referring first to the arrangement shown 50 in Figs. 1 to 4 inclusive, I have shown portions of a cabinet piano player having a case 1 provided with a tracker board 2 and a take-up roll 3 in the usual manner. The action involving a series of power pneu-

matics 4, 4, is arranged below the tracker 55 board, and the pouch board 5 below the pneumatics in the way common in cabinet piano players. It is understood that there is also a suitable motor for driving the take-up spool 3 and connections, by which the 60 same rotates said spool. As these devices form no part of my present invention and are common in the art, they are not shown and described herein. A small lever 6 is shown as being the lever by which the re- 65 wind mechanism to rotate the take-up spool in one way or to rotate the music spool in the reverse direction to rewind the music, is operated. Another lever 7 is shown as being the usual tempo lever to control the 70 wind current to the motor to vary the speed thereof. The connections for this lever are not shown as they are old in the art and form no part of my present invention. Another lever 8 is shown, and this is the usual 75 choke or accent lever for choking off the wind to cause the playing to be loud or soft or any desired variations between such extremes. This choke valve is shown, being indicated at 9, and being carried by a rod 80 10 which is understood to be connected with the lever 8 by suitable connections which are not shown as such are old and well known and form no part of the present invention. This valve 9 controls a port 11 leading from 85 the V-shaped box 12 forming a vacuum chamber to a chamber 13 which is in direct communication with the action through a port 14. A second port 15 is shown establishing communication between the box 12 90 and chamber 13. The wind always can pass between the action and box through the port 15, but can be shut off more or less from the port 11 by the valve 9 to choke down and soften the playing in the usual way. In accordance with my invention, I provide a third or supplemental port 16 also establishing communication between the box 12 and action, by way of the chamber 13. This port is controlled by a valve 17 which is carried by 95 a spindle 18 connected with a rod 19 which latter is in turn connected with a cross-rod 20 having a down-turned end 21. The rod 20 is provided with a crank 22 which is connected with a link 23 which latter is in turn 100 connected with a crank 24 on a spindle 25 carrying a crank 26. The crank 26 is in turn connected with a rod 27 which is in

turn connected with a crank 28 on a spindle 29 having a second crank 30. The latter is connected with a short rod 31 whose upper end is provided with a button 32. The latter is so located as to be convenient to one operating the player, as for example near and between certain of the rods or levers 6, 7 and 8. Thus by actuating the button 32, more or less wind will be permitted to pass between the action and the box 12, whereby a difference in the intensity of the playing will be brought about. If at any time it is desired to accent a note or series of notes, the button 32 is depressed, thereby quickly 15 opening the port 16 and instantaneously increasing the wind power in the action to produce a quick and effective accent of the note or series of notes passing the tracker at that time. This can be done, it will be 20 seen, when the playing is under control of the choke valve 9 in the usual way, so that the accent can be brought about whether the playing is loud or soft or graduated in between. This makes accent easy and simple 25 and instantaneous, and avoids the clumsy and slow method of endeavoring to obtain accent, now in vogue, of operating the pedals slowly, or rapidly and with great force, in order to produce quickly a surplusage of 30 wind power between two consecutive notes or series of notes. The additional wind power to produce the desired accent, can be secured by this invention, by simply pressing the key 32, no matter what the condition 35 of the choke valve 9, instead of endeavoring to produce a quick increase of wind power by a sudden agitation of the foot pedals. The port 14 between the chamber 13 and action, is controlled by a gate valve 33 which is understood to be suitably connected with the rewind apparatus, so as to be thrown across the port 14 to close the same when the rewind is taking place. The usual governor 34 for governing the supply 40 of wind to make the playing uniform whether the number of notes played be large or small, is arranged in connection with the box 12 in the usual way. A lever 35 is shown, being the lever which is connected 45 with suitable mechanism for actuating the sustaining pedal of the piano.

Referring to the arrangement shown in Figs. 5 to 8 inclusive, the invention is shown applied so as to permit independent accent 55 of either the bass or the treble, or the entire action. In this arrangement the same general arrangement and construction of cabinet piano player is shown. The action, however, is divided, as by a partition 36, and the two parts of the action are provided 60 with separate ports 37 and 38. There are two choke valves 39, 39 (Fig. 6) controlling the ports 37 and 38, for softening down the action in the usual way, and these are understood 65 to be connected together as shown

in Fig. 5^a, and operated in unison by the usual expression lever 8, which is connected to rod 70. Below the ports 37, 38 are supplemental ports 40 and 40^a which are controlled by independent accent valves 41, 42. These are controlled by connecting links and rods similar to those described in connection with the device of Figs. 1 to 4 inclusive, so that they can be independently operated by buttons 43 and 44, located at the front of the 75 machine near the other controlling instrumentalities. The ports 40, 40^a open into a channel provided by a channel bar 45. This channel bar 45 is arranged in the box 12 and extends from the same to a supplemental 80 reservoir 46 mounted on the main feeder board. Another channel bar 45^b extends from the supplemental reservoir 46 to the main box 12 and is provided with apertures 51 opening into the latter. Governors or 85 controllers 47 and 48 are mounted on the main board of the bellows on opposite sides of the box 12; the governor 47 is for the treble and the governor 48 for the bass. Small channel blocks 52 and 53 are extended 90 between the governor 47 and the box 12, the channel block 52 opening into the port 38 and the channel bar 53 opening into the interior of the bellows. The governor 47 is provided with a valve 54^a automatically controlling the wind supply passing through the channel block 53. In a similar way channel blocks 54 and 55 extend between the governor 48 and box 12, the former opening into the port 37 and the 100 latter into the reservoir, and the governor 48 being provided with a valve 56 automatically controlling the wind supply passing through the block 55. The usual feeders 57 are arranged on the front of the bellows and 105 provided with straps 58, 58 which are understood to be connected with the pedals in the usual way. Thus the action of the feeders draws the air out of the box 12, and this in turn draws air from the usual 110 reservoir 49 mounted on the box 12. By means of the channel bar 45^b air is also drawn from the supplemental or accent reservoir 46. In this way a condition of 115 vacuum is created in the box 12, and both the reservoirs 49 and 46. From the latter 120 communication is established between the ports 40 and 40^a by means of the channel bar 45, so that air can be withdrawn from the action by means of the ports 40 and 40^a and the supplemental reservoir 46. In a 125 similar manner air can be withdrawn from the action through the channel blocks 52 and 54 communicating with the ports 37 and 38, and in its passage is automatically controlled by the two governors 47 and 48. The wind pressure on the action from the main reservoir thus acts separately upon the treble and bass, and each of these parts of 130 the action is automatically controlled by one

of the governors 47 and 48. The supplemental or additional wind pressure which is added for the purpose of accent, is supplied through the supplemental reservoir 46 to either the treble or bass or both as desired. The usual wind controlling valves 39, 39 controlled by the lever 8, operate to vary the wind pressure or supply on the entire action, and this can be controlled to gradually soften down the playing or to make the same louder, which can be done either gradually or quickly by the lever 8. The accent or supplemental pressure is controlled by the valves 41, 42, and connecting mechanism actuated by the buttons 43 and 44. Thus while the entire action is being controlled, accent can be applied to either the bass or the treble alone, or if desired, to both together, by operating both buttons 43 and 44 simultaneously. In order to prevent the accent pressure from withdrawing air from the box 12 through the ports 37 and 38, check valves 60, 60, are arranged to permit suction through the port 37 away from the action, but to prevent the passage of wind toward the action. Gate valves 50, 50 are provided to shut off wind from the entire action, by closing ports 61, 61. These gate valves 50, 50, are understood to be connected with the rewind lever 6 in any usual or preferred way so as to be operated to cut off the wind when the rewind is taking place. If desired, the supplemental reservoir can be omitted altogether, and the accent pressure communicated to the two parts of the action directly from the vacuum chest formed by the box 12, as in the case of the device of Figs. 1 to 4. In such case the channel bars 45 and 45^b would be omitted, and the ports 40, 41 would open directly into the bellows 45^a. In the arrangement of Figs. 1 to 4, if desired, the supplemental accent reservoir can be added. It will be understood that in this divided action arrangement, the divisions of the action can be more than the two herein shown, and each part can be independently accented. It will also be understood that the invention can be applied to an interior player mechanism, as well as to an exterior or cabinet form of piano player. It will be further understood that the accenting devices could be operated by means other than push buttons and mechanical connections as shown herein. It will be understood that further changes and modifications can be made without departing from the spirit of the invention.

What I claim is:—

1. The combination with a single pneumatic action chest, of a main storage reservoir and two channels connecting said reservoir and said action chest, a low tension bellows in one of said channels, and valves for both of said channels, the valve in the

one of said channels which connects with said low tension bellows being intermediate said bellows and said action chest.

2. The combination of a divided action, a wind inducing apparatus comprising a vacuum chamber, a plurality of passages connecting each part of the divided action and the vacuum chamber, mechanically connected valves for controlling the pneumatic pressure for both sides of the action in unison, independently operable valves for controlling the pressure of the other passage for either side of the action, and a channel communicating with all of said second-mentioned valves and with the wind inducing apparatus.

3. The combination with a divided action, of a wind inducing apparatus comprising a vacuum chamber, an auxiliary reservoir, a plurality of communicating passages between each part of the divided action and the vacuum chamber, valves for controlling the pneumatic pressure for both sides of the action in unison, independently operable valves for controlling the pressure of the other passages for either side of the action, and a channel communicating with all of said second mentioned valves and with the wind inducing apparatus.

4. The combination with a divided action, of a bellows and feeders, and a main and supplemental reservoir, separate governors for controlling the wind pressure on the different parts of the action, means for establishing communication between the main reservoir and the different divisions of the action through said separate governors, valves in said means intermediate said governors and the different parts of the action, means for establishing communication between the supplemental reservoir and the action, and means for controlling communication between the main and supplemental reservoirs and the different divisions of the action.

5. The combination with the feeders and bellows, and main and supplemental reservoirs, of a divided action and independent governors for controlling the wind supply to the different divisions of the action, channel blocks extending between the bellows and supplemental reservoir for establishing communication between said bellows and supplemental reservoir and between the latter and the different divisions of the action, channel blocks extending between the main reservoir and governors and between the latter and the different parts of the action, valves controlling the wind pressure on the action from the main reservoir, and separate valves for independently controlling the wind supply on the action from the supplemental reservoir, and means for preventing communication between the main and supplemental reservoirs.

6. The combination with a divided action of a wind inducing apparatus comprising a vacuum chamber, a plurality of wind ways connecting each part of the divided action and the vacuum chamber, one of the wind ways for each part of the action being provided with a valve for controlling the pneumatic pressure for all of the actions in unison, and having a supplemental reservoir connected therewith and independently operable valves in each of the main wind ways of each part of the action, for accenting any part of the action at will.
7. In a pneumatic instrument in combination, a source of air tension, a divided action, a plurality of channels leading from said

source of tension to each side of said action, an independent governor for one of said channels for each side of the action, a supplemental reservoir for controlling two other of said channels, one for each side of the action, valves operable in unison for controlling said first-mentioned channels and independently operable valves for controlling said second-mentioned channels. 25

In witness whereof, I hereunto subscribe my name this 15th day of April A. D., 1905.

ANDREW M. BELFIELD.
